Primary Examiner — Lauren R Calve(74) *Attorney, Agent, or Firm* — Kelly & Kelley, LLP(57) **CLAIM**

The ornamental design for a packaging for toothflosser and mint, as shown.

DESCRIPTION

FIG. 1 is a top, front and right-side perspective view of packaging for toothflosser and mint embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top, front and right-side perspective view of packaging for toothflosser and mint according to a second embodiment; and,

FIG. 9 is a top plan view of the embodiment of FIG. 8.
